 American Heist and Derrick Company, St.
 Paul, Minn., a corporation of Delaware

Application May 2, 1936, Serial No. 77,555

25 Claims. (Cl. 105—28)

The present invention has relation to a crane, or like machine.

An object of the invention is to provide in a crane, or like machine, a novel and improved 5 swivel joint for conveying or transporting a fluid between a supporting structure and a platform revolvable thereon, either from the supporting structure to the revolvable platform, or from the revolvable platform to the supporting structure.

A further object is to provide in a crane, or like machine, a novel and improved swivel joint for conveying or transporting a fluid, such as steam, from or to a supporting member to or from a supported member revolvable upon the supporting member.

A further object is to provide in a crane, or like machine, a novel and improved steam conveying or transporting swivel joint for carrying operating steam from a source of steam supply on a car body to steam actuated mechanism on a platform mounted to have revolvable movement 20 upon a car body.

A further object is to provide a crane, or like machine, which will include a car body having thereon a revolvable platform and steam actuated mechanism on the revolvable platform for operating workable elements of, and/or for propelling the crane or machine, and will also include a second car body having thereon a steam boiler, or other source of steam supply for operating said steam actuated mechanism, and means 30 for conveying operating steam from said boiler or source of steam supply to said steam actuated mechanism.

A further object is to provide a crane, or like machine, which will include steam actuated mechanism upon a revolvable platform carried by a car body, a source of steam supply for the steam actuated mechanism upon a different car body, and novel and improved means for conveying operating steam from the source of steam supply to the steam actuated mechanism.

A further object is to provide a crane, or like machine, which will include a pair of connected car bodies having supporting wheels and adapted 45 to be transported as a unit, a revolvable platform on one of the car bodies, steam actuated mechanism on the revolvable platform for operating workable elements of the crane, as the drums, boom, compressor for providing air brake supply air, etc., and/or for propelling the crane unit in either direction, a boiler for steam, or other source of steam supply, on the other car body, and novel and improved means for conveying operating steam for the steam actuated mechanism

from said boiler or source of steam supply to said steam actuated mechanism.

A further object is to provide a crane, or like machine, which will include a car body having thereon wheels and a platform revolvable about a vertical axis, steam actuated mechanism on the revolvable platform for propelling the crane or machine, and a drive shaft for accomplishing propulsion of the crane or machine extending along, or coinciding with, the vertical axis for 10 said platform and having its upper portion arranged to be driven by said steam actuated mechanism and its lower portion arranged to drive the wheels of said car body, and will also include a second car body having wheels and connected to the car body first mentioned and having thereon a steam boiler, or other source of steam supply for operating the steam actuated mechanism, and a novel and improved steam conveying or transporting swivel joint in surrounding 15 relation to said drive shaft for carrying operating steam from said steam boiler or other source of steam supply to said steam actuated mechanism.

A further object is to provide a crane, or like machine, which will include a car body having thereon wheels, air brakes for said wheels, and a platform revolvable about a vertical axis, steam actuated mechanism on the revolvable platform for propelling the crane or machine, a drive shaft 20 for accomplishing propulsion of the crane or machine extending along, or coinciding with, the vertical axis for said platform and having its upper portion arranged to be driven by said steam actuated mechanism and its lower portion arranged to drive the wheels of said car body, air 25 brake mechanism upon the revolvable platform, and an air brake pipe extending from said air brake mechanism along the axis for said platform to said air brakes, and will also include a second car body having wheels and connected to the car body first mentioned and having thereon a steam boiler, or other source of steam supply for operating said steam actuated mechanism, and novel and improved means including a steam 30 conveying or transporting joint in surrounding relation to said drive shaft and said air brake pipe for carrying operating steam from said boiler or other source of steam supply to said steam actuated mechanism.

And a further object is to provide a crane, or like machine, which will include a car body having thereon wheels, air brakes for said wheels, and a platform revolvable about a vertical axis, steam actuated mechanism on the revolvable 35

platform for propelling the crane or machine, a hollow drive shaft for accomplishing propulsion of the crane or machine extending along, or coinciding with, the vertical axis for said platform and having its upper portion arranged to be driven by said steam actuated mechanism and its lower portion arranged to drive the wheels of said car body, air brake mechanism on the revolvable platform, and air brake pipes extending from said air brake mechanism and downwardly through said hollow drive shaft, said air brake pipes being arranged in spaced apart, surrounding relation to each other, and one of the air brake pipes leading to the before mentioned air brakes, and will also include a second car body connected to the car body first mentioned and having thereon a steam boiler, or other source of steam supply for operating said steam actuated mechanism, wheels with air brakes for said second car body, an air brake line common to the air brakes for the wheels for both said car body and said second car body, one of the before mentioned air brake pipes leading from the air brake mechanism on said revolvable platform to said common air brake line, and novel and improved means including a steam conveying or transporting swivel joint in surrounding and clearing relation to said drive shaft and said air brake pipes for carrying operating steam from said boiler, or other source of steam supply upon said second car body, past or through the first mentioned car body and its revolvable platform to the steam actuated mechanism upon said revolvable platform.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawings forming a part of this specification,

Fig. 1 is a side elevational view of a crane, or like machine, in which the features and characteristics of the invention are incorporated, parts being in section, other parts being omitted, and still other parts being broken away;

Fig. 2 is a detail sectional view of the mounting for the revolvable platform of the machine and an arrangement for revolving the platform;

Fig. 3 is an enlarged, fragmentary, transverse, vertical sectional view of the machine, taken on line 3—3 in Fig. 1, detailing features of the invention;

Fig. 4 is an enlarged, fragmentary, longitudinal, vertical sectional view of the machine, taken substantially at a right-angle to the disclosure of Fig. 3, further detailing some of the features shown in said Fig. 3, and detailing additional features at higher elevation in the machine; and

Fig. 5 is an enlarged, fragmentary, vertical sectional view, taken as on line 5—5 in Fig. 4.

With respect to the drawings and the numerals of reference thereon, the crane, or like machine, includes a car body or frame 10 having bearings 11 for axles which support traveling wheels 12. The machine is adapted to be self propelled, as well as propelled by a locomotive, along the track 13. The car body or frame 10 may be of any or-

dinary or preferred construction. Air brakes on said car body or frame for the wheels 12, are designated generally at 14. A train air brake line for the air brakes 14 is indicated 15. When the crane or machine is propelled by a locomotive, the air brake line 15 is connected up in usual manner so that the air brakes 14 can be operated from the cab of the locomotive, in common with all of the cars of a train, in a well known manner.

A second car body or frame of the crane or machine is represented at 16. Said second car body or frame 16 is adapted to be propelled by the car body or frame 10, or by a locomotive, and to this end the car body or frame 16 is coupled, as at 17, to the car body or frame 10. The car body or frame 16 has bearings 18 for axles which support traveling wheels 19. Said car body or frame 16 may likewise be of any ordinary or preferred construction. Air brakes, denoted generally at 20, on the car body or frame 16 are for the wheels 19. The air brakes 20 are connected to the air brake line 15.

A bull gear 21 rests squarely upon and is connected to the upper surface of the car body or frame 10. Said bull gear is arranged concentric to a vertical hollow shaft 22, which hollow shaft constitutes a vertical axis or, in effect, a king pin of the crane or machine about which a platform, represented at 23, revolves, and also constitutes a drive shaft passing through the car body or frame 10 and through the revolvable platform 23. The bull gear 21 includes an external, vertically disposed gear surface or toothed portion 24, and an inner, circumferential portion providing a lower operative rail 25 in the machine. The vertical hollow shaft 22 is suitably mounted at its lower portion, as at 26, in the car body or frame 10, and passes freely or loosely, as at 27, through the upper wall or surface 28 of said car body or frame. The platform 23 is revolvably mounted by employment of an upstanding bearing 29 upon said platform which receives the hollow shaft 22, a circumferential upper operative rail 30 upon the base of the platform and directly above the lower operative rail 25, and rollers 31, engaging the lower operative rail 25 of the bull gear 21 and engaged by said upper operative rail 30 upon said platform, upon a container ring represented generally at 32.

Mechanism for revolving the platform 23 in either direction may include a short vertical shaft 33 mounted in said platform 23 and extending a short distance above and below the platform. As disclosed, a gear 34 is fixed to the upper portion of the short shaft 33 and a pinion 35 is fixed to the lower portion of said shaft. Said pinion 35 meshes with the gear surface of toothed portion 24 of the bull gear. The gear 34 meshes with a pinion 36 upon a second short vertical shaft 37 suitably mounted in the platform, and the upper end portion of the short shaft 37 fixedly carries a bevel gear 38 arranged above the platform. Any suitable means may be employed to drive the bevel gear 38 in either direction to thus revolve the platform. Evidently, when the bevel gear 38 is turned, the vertical shaft 33 and the pinion 35 will also be turned. Rotation of said pinion 35 will cause it to ride along the gear surface or toothed portion 24 of the bull gear 21 fixed to the car body or frame 10, and thus cause the platform to be revolved upon its axis a distance corresponding to the extent of rotation of the short shaft 33.

The revolable platform may carry all of the usual appurtenances found upon the platforms of cranes, excavators, or like machines. As disclosed, numeral 39 denotes drums, 40 steam actuated mechanism, 41 a tank for compressed air, and 42 indicates valve structure for handling compressed air, upon said revolable platform 23.

The hollow shaft 22 includes a bevel gear 43 upon its upper portion and above the platform 23 which meshes with a bevel gear 44 driven by the steam actuated mechanism 40, and includes a bevel gear 45 upon its lower portion which meshes with a bevel gear 46 upon a driven shaft 47 mounted in the car body or frame 10 and suitably connected up to drive the traveling wheels 12. Obviously, operation of the steam actuated mechanism drives the wheels 12 in direction depending upon the direction of operation of said steam actuated mechanism.

The car body 16 carries a steam boiler 48 adapted to contain a source of steam supply for operating the steam actuated mechanism 40. Steam is conveyed from the boiler 48 to said steam actuated mechanism 40 by novel and improved means, indicated generally at 49, of character and construction presently to be described. A steam pipe connection 50 leads from the steam boiler 48 to said means 49 and a steam pipe connection 51 leads from the means 49 to the steam actuated mechanism 40. The pipe connection 50 leads vertically downward from the top of the boiler 48 at one side thereof to about the elevation of the upper part of the car body or frame 16, and thence leads horizontally along a side of the upper portion of the car body or frame 10 and thence inwardly on said car body or frame 10 to the means 49. The horizontal portion of said pipe connection 50 includes an expansible coupling 52 situated between the car bodies or frames 10 and 16 to make provision for relative swinging movement of said car bodies or frames, and as disclosed said horizontal portion of the pipe connection 50 is supported upon the car body or frame 10, as at 53.

An air compressor 54 for supplying air to the compressed air tank 41 is supported upon said tank 41. As shown, said air compressor 54 is actuated by steam led thereto by a pipe connection 55 from the pipe connection 51. Numeral 56 represents an exhaust outlet from the steam actuated mechanism 40, and 57 indicates an exhaust outlet from the air compressor 54.

The valve structure 42 includes a straight air brake valve 58 and an automatic air brake valve 59. An air connection 60 leads from the compressed air tank 41 to each air brake valve 58 and 59. The air brake valve 58 controls compressed air from the tank 41 and the air connection 60 for directly operating the air brakes 14, and the air brake valve 59 controls compressed air from said tank 41 and air connection 60 for use in the train air brake line 15 to operate all of the air brakes 14 and 20. To this end, an air brake pipe or connection 61 extends from said air brake valve 58 to said air brakes 14, and an air brake pipe or connection 62 extends from said air brake valve 59 to said train air brake line 15.

The air brake pipe or connection 61 includes a vertical portion 63 thereof suitably and centrally mounted within the hollow drive shaft 22, and the air brake pipe or connection 62 includes a vertical portion 64 thereof mounted within said hollow drive shaft 22 in spaced and surrounding relation to said vertical portion 63.

A cap 65, including necks, denoted 66 and 67, respectively, rotatably mounted in fluid-tight manner upon the upper ends of said vertical portions 63 and 64 and situated above the hollow drive shaft 22, supports a pipe 68 of the connection 61 leading from the air brake valve 58 to the vertical portion 63 and a pipe 69 of the connection 62 leading from the air brake valve 59 to the vertical portion 64.

A fitting 70, connected to the lower ends of the vertical portions 63 and 64 and situated below the hollow drive shaft 22, includes a passageway 71 leading from the vertical portion 63 to a pipe 72 of the connection 61 extending to one side of the car body or frame 10 and to the air brakes 14, and a passageway 73 leading from the vertical portion 64 to a pipe 74 of the connection 62 extending to the other side of said car body or frame 10 and to the train air brake line 15.

Thus, it will be seen, the crane or machine includes straight air brakes upon the car body or frame 10 operable directly from the air brake valve 58, and also includes automatic air brakes upon both said car body or frame 10 and the car body or frame 16 operable from the air brake valve 59 and through the instrumentality of the train air brake line 15. When the steam actuated mechanism is inoperative and the air brake line 15 is connected to a locomotive, the air brakes upon the car bodies or frames 10 and 16 are operable from the cab of the locomotive, as will be apparent.

The novel and improved means 49 is constituted as a swivel joint including a disc top member 75 bolted up against the lower surface of the revolable platform 23, as at 76, in surrounding relation to the hollow drive shaft 22 which constitutes the vertical axis about which said platform 23 is revolved. As designated at 77, the disc top member 75 of the swivel joint includes a central opening freely receiving said hollow drive shaft 22. Also, said disc top member 75 includes a shallow, horizontally disposed, annular groove 78 in its lower surface, and said shallow groove 78 extends about a complete circumference of the top disc member 75 which is concentric with the vertical hollow drive shaft or axis 22. The pipe connection 51, leading from the means 49 to the steam actuated mechanism 40, is threadedly received, as at 79, in the disc top member 75 to afford communication between the shallow, annular groove 78 and said steam actuated mechanism 40. Said pipe connection 51 passes through an opening 80 in the revolable platform 23.

The swivel joint 49 also includes a bottom member 80 constituted as an annular trough having an annular, horizontally disposed base 81 situated directly beneath and in spaced relation to the shallow, annular groove 78, an inner, upstanding circular wall 82 adjacent the inner, circular margin of said shallow, annular groove 78, and an outer, upstanding circular wall 83 adjacent the outer, circular margin of the shallow, annular groove 78. Said inner, upstanding circular wall 82 integrally supports a horizontal, inwardly extending, annular flange 84 against which an annular portion 85 of the lower surface of the disc top member 75 adjacent the inner, circular margin of the shallow, annular groove 78 is rotatably seated, and said outer, upstanding circular wall 83 integrally supports a horizontal, outwardly extending annular flange 86 against which an annular portion 87 of the lower surface of said disc top member 75 adjacent the outer, circular margin of said shallow, annular groove 78 is rotatably seated.

seated. The annular trough or bottom member 80 and its upstanding inner and outer circular walls 82 and 83 are concentric with the hollow drive member or axis 22, as well as directly beneath the shallow, annular groove 78. The disc top member 75 is rotatable with the platform 23 and relatively to the annular trough or bottom member 80. Evidently, said members 75 and 80 together constitute a closed, annular chamber, denoted 88, which is at all times in communication with the steam pipe connection 51 leading from the swivel joint or means 49 to the steam actuated mechanism 40. The steam pipe connection 50, leading from the steam boiler 48 to said swivel joint or means 49, is threadedly received, as at 89, in the horizontal base 81 of the bottom member 80 to be in constant communication with said closed, annular chamber 88.

The horizontal, inwardly extending, annular flange 84 upon the inner, upstanding circular wall 82 and the annular portion 85 of the lower surface of the disc top member 75 are held in engaging, relatively rotatable relation to each other by an inner, annular retaining member 91 for the annular trough or bottom member 80. Said retaining member 91 includes an opening 92 clearing the vertical hollow drive shaft 22, and also includes an outer, vertical, circumferential surface 93 in spaced relation to the inner, upstanding circular wall 82 and at the elevation of said wall 82. A horizontal, outwardly extending, annular flange 94 upon the upper portion of the annular retaining member 91 includes a horizontal upper surface 95 upon which the horizontal, inwardly extending, annular flange 84 rotatably rests, while also in engagement with said annular portion 85, and said annular flange 94 also includes an outer, vertical, circumferential surface 96 in contiguous and rotatable relation to an inner, vertical, circumferential surface 97 of the inner, upstanding circular wall 82. The upper surface of the body of the annular retaining member 91 is fitted up against the lower surface of the disc top member 75. An inner packing 98 is situated in the annular space between the circumferential surfaces 93 and 97 and beneath the annular flange 94, and an inner, annular packing retainer 99 includes an upper, vertical, annular portion 100 in the annular space between said circumferential surfaces 93 and 97 and holding the packing 98 in engagement with the lower surface of the annular flange 94. Said annular packing retainer 99 also includes a lower, inwardly extending, horizontal portion 101 beneath and in spaced relation to the annular retaining member 91. Headed and nutted screw bolts 102 fasten the retaining member 91 up against the disc top member 75, and headed and nutted screw bolts 103 assist in fastening said retaining member to said disc top member and also tightly retain the upper, vertical, annular portion 100 of the annular packing retainer 99 within the annular space between the circumferential surfaces 93 and 97 and in proper engagement with the packing 98. The headed and nutted bolts 102 pass through the disc top member 75 and the annular retaining member 91, and the headed and nutted bolts 103 pass through said disc top member and annular retaining member and also pass through the lower, horizontal portion 101 of the annular packing retainer 99. Said horizontal portion 101 includes an opening 104 about the hollow drive shaft 22. It will be seen that the inner, annular retaining

member 91 and the inner, annular packing retainer 99 are fixed to rotate with the disc top member 75, and that the annular trough or bottom member 80 and said disc top member, inner, annular retaining member and inner, annular packing member, as a unit, are relatively rotatable.

The horizontal, outwardly extending annular flange 86 upon the outer, upstanding circular wall 83 and the annular portion 87 of the lower surface of the disc top member 75 are held in engaging, relatively rotatable relation to each other by an outer, annular retaining member 105 for said annular trough of bottom member 80. Said retaining member 105 includes an inner, vertical, circumferential surface 106 in spaced relation to the outer upstanding circular wall 83 and at the elevation of said wall 83. A horizontal, inwardly extending annular flange 107 upon the upper portion of the annular retaining member 105 includes a horizontal upper surface 108 upon which the horizontal, outwardly extending, annular flange 86 rotatably rests, while also in engagement with said annular portion 87, and said annular flange 107 also includes an inner, vertical, circumferential surface 109 in contiguous and rotatable relation to an outer, vertical, circumferential surface 110 of the outer, upstanding circular wall 83. The upper surface of the body of the annular retaining member 105 is fitted up against the lower surface of the disc top member 75. An outer packing 111 is situated in the annular space between the circumferential surfaces 106 and 110 and beneath the annular flange 107, and an outer, annular packing retainer 112 includes an upper, vertical, annular portion 113 in the annular space between said circumferential surfaces 106 and 110 and holding the packing 111 in engagement with the lower surface of the annular flange 107. Said annular packing retainer 112 also includes a lower, outwardly extending, horizontal portion 114 beneath and in spaced relation to the annular retaining member 105. Headed and nutted screw bolts 115 fasten the retaining member 105 up against the disc top member 75, and headed and nutted screw bolts 116 assist in fastening said retaining member to said disc top member and also tightly retain the upper vertical annular portion 113 of the annular packing retainer 112 within the annular space between the circumferential surfaces 106 and 110 and in proper engagement with the packing 111. The headed and nutted bolts 115 pass through said disc top member and annular retaining member 105, and the headed and nutted bolts 116 pass through said disc top member and annular retaining member and also pass through the lower, horizontal portion 114 of the annular packing retainer 112. The outer, annular retaining member 105 and the outer, annular packing retainer 112 are fixed to rotate with the disc top member 75, and the annular trough or bottom member 80 and said disc top member, outer, annular retaining member and outer, annular packing member, as a unit, are relatively rotatable.

As will be quite clear from the drawings, the swivel joint including the disc top member 75 and the annular trough or bottom member 80 is disposed at elevation somewhat above the car body or frame 10, and is not connected to said car body or frame. Instead, said annular trough or bottom member 80 of the swivel joint is held against turning movement, when the platform 75

23 and the disc top member 75 are revolved upon the car body or frame, through the instrumentality of a stop member 117 fixed upon the car body or frame, as at 118, and a stop element 119 5 upon the annular trough or bottom member 80 engaged by said stop member. As disclosed, the stop member 117 includes spaced apart, upstanding legs 120, and the stop element 119 is constituted as a lug or strip upon the base 81 of the 10 annular trough or bottom member 80 extending downwardly, more or less loosely, between said upstanding legs 120. The lug or strip 119 and the upstanding legs 120 extend transversely of the annular base 81 at one side thereof. Obviously, 15 when the platform and disc top member 75 with annular retaining members 91 and 105 and annular packing retainers 99 and 112 are revolved, in either direction, about the hollow drive shaft or axis 22, the stop element 119 by engagement with one or the other of the upstanding legs 120 retains the annular trough or bottom member 80 against rotative movement upon the car body or frame 10. At the same time, relative swinging movement between the platform 23 20 and said car body or frame 10 can have no detrimental effect upon the swivel joint, it being evident that tilting or rocking movement of the revolvable platform upon its vertical axis will simply, cause the stop element, lug or strip 119 25 to move freely, upwardly and downwardly and inwardly and outwardly, in the slot between the upstanding legs 120.

Or, stated otherwise, the annular trough or bottom member 80 is secured to and carried by the disc top member 75, itself rigidly supported upon the revolvable platform 23, and said annular trough or bottom member is, at the same time, mounted so there can be relative rotary movement between the annular trough or bottom member and said disc top member 75. Also, said annular trough or bottom member 80 is in spaced relation to and entirely clear of the car body or frame 10, and is held against rotation relative to said car body or frame by a tongue 40 and slot arrangement adapted to the purpose of permitting free tilting, swinging and/or rocking movement of the revolvable platform and the car body or frame relatively to each other without in any manner exerting detrimental action upon the upper and lower elements of the swivel joint which would have tendency to destroy said swivel joint and to render it unfit to properly convey or transport steam.

It will be apparent that were the annular trough or bottom member 80 directly or rigidly attached to the car body or frame 10, all of the relative tilting, swinging and/or rocking movements between the revolvable platform 23 and said car body or frame would have to be resisted and absorbed by the elements of the swivel joint which hold the disc top member 75 and said annular trough or bottom member 80 to each other. Obviously, said relative tilting, swinging and/or rocking movements would in a short time 50 completely destroy the swivel joint. In the arrangement as illustrated and described, the only action which can possibly be exerted upon the elements of the swivel joint is the rotative action of the revolvable platform which causes the stop element 119 to be brought into pressing engagement with one or the other of the legs 120. The resultant force thus exerted upon the swivel joint is in direction exactly counter to the direction of rotation of said revolvable platform, and the disc 55 top member, with its appurtenances, revolves

easily, smoothly and evenly upon the stationarily held annular trough or bottom member. There is no structure present which could exert influence upon the disc top member 75 and the annular trough or bottom member 80 in direction tending to disconnect said members 75 and 80 by tearing them apart, and, hence, there is in the crane or machine no possibility of the swivel joint becoming impaired and unfit for its purpose even after very long and continued use. Tilting, 10 swinging and/or rocking movements between the revolvable platform 23 and the car body or frame are possible without disengaging the threaded pipe connection 50 from the horizontal base 81 of the member 80. In an installation the pipe 15 connection 50 need not necessarily be tightly fixed in its support. And, too, said pipe connection 50 has some flexibility. The pipe connection can, actually, be loosely supported. Disengagement of the pipe connection is no problem 20 in practice.

The crane or machine as illustrated in the drawings and as hereinbefore fully described is constituted as a self-contained unit including two car bodies or frames each with traveling wheels 25 and air brakes. Also, each car body or frame of the self-contained unit includes thereon a common train air brake line. The car body or frame 10 supports a revolvable platform 23 which carries a steam engine or engines, compressed air for air 30 brakes and air brake valves, and may carry all appurtenances usually found upon the turntable of a crane, or like machine. As disclosed, the revolvable platform 23 carries mechanism for operating straight air brakes for the wheels 12 of 35 the car body or frame 10, whereby the car including this car body or frame can be brought to a stop independently of the train line braking system. Said revolvable platform 23 also carries mechanism for operating automatic air brakes 40 through the instrumentality of an air brake line including the air brakes upon both car bodies or frames 10 and 16. And the arrangement is such that the air brakes upon the car bodies or frames 45 10 and 16 can be operated from the cab of a locomotive through the instrumentality of a train air brake line including said air brakes upon said car bodies or frames 10 and 16 as a part thereof, when the two car unit constituting the crane, or like machine, is being transported as a part of a train 50 propelled by a locomotive. The car body or frame 16 carries the steam to be utilized in the steam engine or engines upon the revolvable platform 23 as the actuating medium for said steam engine or steam engines, and the means 49, including the swivel joint as a part thereof, constitutes a completely satisfactory, efficient and dependable construction and arrangement for carrying steam for operating the steam engine or engines from its location upon the car body or frame 55 16 to said steam engine or engines.

While the swivel joint of the invention has been illustrated and described as when applied to convey steam from one car body to a revolvable platform upon a different car body, it is to be understood that the boiler 48 could be mounted upon the car body having the revolvable platform instead of on the separate car body, within the principles of the invention. Also, the crane, or like machine, could be permanently mounted on a barge or base of any known or preferred character and the steam supplied to the revolvable platform from an outside source. The boiler could be mounted on the revolvable platform and the swivel joint used to lead steam from the boiler to 70 75

some auxiliary or other engine, or the like, as for a spud hoist, for an anchor hoist, or for a separate traveling machine.

The swivel joint may find use for fluids other than steam. The air piping disclosed, extending vertically along the axis for the rotatable platform, may in instances not be employed, and in instances a shaft such as 22 may be entirely omitted. Lines other than air piping may lead through the axis or center of the machine, as, for example, water lines, oil lines, electric conduits, and/or operating rods.

What is claimed is:

1. In a machine of the character described, a car body, a platform thereon, a vertical shaft about which said platform is revolvable, steam actuated mechanism on said platform, a different car body, a source of steam supply on said different car body, and means for conveying steam from said source of steam supply to said steam actuated mechanism, said means including a swivel joint consisting of a member surrounding said vertical shaft and secured to said platform, a second member surrounding the vertical shaft and rotatably supported by the member first mentioned to provide a chamber between said member and said second member, a steam connection leading from said source of steam supply by way of said second member to said chamber, a steam connection leading from said chamber by way of said member to said steam actuated mechanism, and a device between the second member and car body and secured upon said car body for precluding rotation of said second member with respect to said car body, said device having engagement with said second member.

2. In a machine of the character described, a car body having traveling wheels, a platform on said car body, a vertical shaft about which said platform is revolvable, a support for said vertical shaft on said car body, steam actuated mechanism on said platform, a different car body having traveling wheels, means coupling said car body and different car body to each other, a source of steam supply on said different car body, and means for conveying operating steam for the steam actuated mechanism from said source of steam supply to said steam actuated mechanism, said last mentioned means including a swivel joint consisting of an annular member surrounding said vertical shaft and secured to said platform, a second annular member surrounding the vertical shaft and rotatably supported by the annular member first mentioned to provide an annular chamber between said annular member and said second annular member, a steam connection leading from said source of steam supply by way of said second annular member to said annular chamber, a steam connection leading from said annular chamber by way of said annular member to said steam actuated mechanism, and a device between the second member and car body and secured upon said car body for precluding rotation of said second annular member with respect to said car body, said device having engagement with said second annular member.

3. In a machine of the character described, a car body having traveling wheels, a platform on said car body, a vertical shaft mounted on said car body about which said platform is revolvable, steam actuated mechanism on said platform, a different car body having traveling wheels, means coupling said car body and said different car body to each other, a source of steam supply on said different car body, and means for conveying

steam for operating the steam actuated mechanism from said source of steam supply to said steam actuated mechanism, said last mentioned means including a swivel joint consisting of an annular member surrounding said vertical shaft and secured to said platform, a second annular member surrounding the vertical shaft and rotatably supported by the annular member first mentioned to provide an annular chamber between said annular member and said second annular member, the second annular member being free from direct connection with said car body, a steam connection leading from said source of steam supply by way of said second annular member to said annular chamber, a steam connection leading from said annular chamber by way of said annular member to said steam actuated mechanism, and a device between the second member and car body for precluding rotation of said second member with respect to said car body, said device being secured upon said car body and having engagement with said second member.

4. In a machine of the character described, a car body having traveling wheels, a platform on said car body, a vertical shaft about which said platform is revolvable, a support for said vertical shaft upon said car body, steam actuated mechanism on said platform, a different car body having traveling wheels, means coupling said car body and different car body to each other, a source of steam supply on said different car body, and means for conveying steam for operating the steam actuated mechanism from said source of steam supply to said steam actuated mechanism, said last mentioned means including a swivel joint consisting of an annular member surrounding said vertical shaft and secured to said platform, a second annular member surrounding the vertical shaft and rotatably assembled with and supported by the annular member first mentioned to provide an annular chamber between said annular member and said second annular member, a steam connection leading from said source of steam supply by way of said second annular member to said annular chamber, an expandible coupling in said mentioned steam connection and at a location between said car body and said different car body, a steam connection leading from said annular chamber by way of said annular member to said steam actuated mechanism, and a device secured upon said car body between the second member and car body and engaged with said second member for precluding rotation of said second member with respect to said car body.

5. In a machine of the character described, a supporting structure, a platform revolvable upon said supporting structure, and means for conveying a fluid between said supporting structure and said revolvable platform, said means including a swivel joint consisting of a member concentric to the axis for the platform and secured to said platform, a second member concentric to said axis and rotatably supported by the first mentioned member to provide a chamber between said member and said second member, said second member being free of direct connection with said supporting structure, a fluid connection by way of said member to said chamber, a fluid connection by way of said second member to said chamber, and means for securing said second member against rotative movement relatively to said supporting structure, said last mentioned means and said second member being adapted to have substan- 75

tially a vertical movement relatively to each other.

6. In a machine of the character described, a car body with traveling wheels, a platform rotatable about a vertical axis of said car body, steam actuated mechanism on said platform, a different car body with traveling wheels, means coupling said car body and said different car body to each other, a source of steam supply on said different car body, and means for conveying steam for operating the steam actuated mechanism from said source of steam supply to said steam actuated mechanism, said last mentioned means including a swivel joint consisting of a member concentric to said vertical axis and secured to said platform, a second member concentric to said vertical axis and rotatably supported by the first mentioned member to provide a chamber between said member and said second member, said second member being free of direct connection with said car body, a steam connection leading from said source of steam supply by way of said second member to said chamber, a steam connection leading from said chamber by way of said member to said steam actuated mechanism, and means for securing said second member against rotative movement relatively to said car body, said last mentioned means and said second member being adapted to have substantially a vertical movement relatively to each other.

7. In a machine of the character described, a car body with traveling wheels, a vertical shaft carried by said car body, a platform rotatable about said vertical shaft, steam actuated mechanism on said platform, a different car body with traveling wheels, means coupling said car body and said different car body to each other, a source of steam supply on said different car body, and means for conveying operating steam for the steam actuated mechanism from said source of steam supply to said steam actuated mechanism, said last mentioned means including a swivel joint consisting of a member surrounding said vertical shaft and secured to said platform, a second member surrounding the vertical shaft and rotatably supported by said member to provide a chamber between said member and said second member, said second member being free of direct connection with said car body, a steam connection leading from said source of steam supply by way of said second member to said chamber, a steam connection leading from said chamber by way of said member to said steam actuated mechanism, and a tongue and slot interengaging device between said second member and said car body for preventing rotative movement of said second member relatively to said car body.

8. In a machine of the character described, a car body with traveling wheels, a vertical shaft on said car body, a platform rotatable about said vertical shaft, steam actuated mechanism on said platform, a different car body with traveling wheels, means coupling said car body and different car body to each other, a source of steam supply on said different car body, and means for conveying operating steam for the steam actuated mechanism from said source of steam supply to said steam actuated mechanism, said last mentioned means including a swivel joint consisting of a member surrounding said vertical shaft and secured to said platform, a second member surrounding the vertical shaft and supported by the first mentioned member to be rotatable relatively to said member on a

horizontal axis and to provide a chamber between said member and said second member, said second member being free of direct connection with said car body, a steam connection leading from said source of steam supply by way of said second member to said chamber, a steam connection leading from said chamber by way of said member to said steam actuated mechanism, and means for securing said second member against rotative movement relatively to said car body, said last mentioned means and said second member being adapted to have substantially a vertical movement relatively to each other.

9. In a machine of the character described, a supporting structure, a platform revolvable upon said supporting structure, and means for conveying a fluid between said supporting structure and said revolvable platform, said means including a swivel joint consisting of a member concentric to the axis for said platform and secured to the platform, a second member concentric to said axis and rotatably supported by the first mentioned member, said member and second member providing a chamber therebetween, fluid connections by way of said member and said second member to said chamber, and a device for precluding rotation of said second member relatively to said supporting structure, said device and said second member being adapted to have substantially a vertical movement relatively to each other.

10. In a machine of the character described, a supporting structure, a structure revolvable upon said supporting structure, and means for conveying a fluid between said supporting structure and said revolvable structure, said means including a swivel joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member to said chamber, and a device engaged with said second member and with the structure other than the one to which said member is secured and operative upon said second member to preclude rotation of the second member relatively to the structure with which said device is engaged.

11. In a machine of the character described, a supporting structure, a structure revolvable upon said supporting structure, and means for conveying a fluid between said supporting structure and said revolvable structure, said means including a swivel joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member to said chamber, and a device secured to one of said structures and to said second member for precluding rotation of said second member relatively to the structure other than the one to which said member is secured, said device and said second member being adapted to have substantially a vertical movement relatively to each other.

12. In a machine of the character described, a supporting structure, a structure revolvable about

a vertical axis of said supporting structure, and means for conveying a fluid between said supporting structure and said revolvable structure, said means including a swived joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member to said chamber, and a device for precluding rotation of said second member relatively to the structure other than the one to which said member is secured, said device and said second member being adapted to have substantially a vertical movement relatively to each other.

13. In a machine of the character described, a car body, a revolvable platform thereon, steam actuated mechanism on said revolvable platform, a different car body, a source of steam supply on said different car body, and means for conveying steam from said source of steam supply to said steam actuated mechanism, said means including a swivel joint free of direct connection with said car body and having one element thereof fixed to said revolvable platform and another element thereof carried by and relatively rotatable with respect to the first mentioned element, said elements together providing a chamber, a steam connection leading from said source of steam supply to said chamber, a steam connection leading from said chamber to said steam actuated mechanism, and a device connected to the car body and said other element for precluding rotation of said other element of said swivel joint relatively to said car body.

14. In a machine of the character described, a supporting structure, a structure revolvable upon said supporting structure, and means for conveying a fluid between said supporting structure and said revolvable structure, said means including a swivel joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member to said chamber, and a tongue and slot interengaging device between and connected to said second member and the structure other than the one to which said member is secured for preventing rotative movement of the second member relatively to said last mentioned structure.

15. In a machine of the character described, a supporting structure, a structure revolvable upon said supporting structure, and means for conveying a fluid between said supporting structure and said revolvable structure, said means including a swivel joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member to said chamber, and a tongue and slot interengaging device between said second member and the structure other than the one to which said mem-

ber is secured for preventing rotative movement of the second member relatively to said last mentioned structure, said device and said second member being adapted to have substantially a vertical movement relatively to each other.

16. In a machine of the character described, a supporting structure, a structure revolvable about a vertical axis upon said supporting structure, and means for conveying a fluid between said supporting structure and said revolvable structure, said means including a swivel joint mounted in its entirety upon one of said structures and free of direct connection with the other structure, and said swivel joint consisting of a member concentric to the axis for the rotatable structure and secured to one of said structures, a second member concentric to said axis and rotatably assembled with the first mentioned member, the member and second member providing a chamber therebetween, fluid connections by way of said member and said second member to said chamber, and a tongue and slot interengaging device between said second member and the structure other than the one to which said member is secured for preventing rotative movement of the second member relatively to the last mentioned structure.

17. In a machine of the character described, a supporting structure, a structure revolvable about a vertical axis upon said supporting structure, and means for conveying a fluid between said supporting structure and said revolvable structure, said means including a swivel joint mounted in its entirety upon one of said structures and free of direct connection with the other structure, and said swivel joint consisting of a member concentric to the axis for the rotatable structure and secured to one of said structures, a second member concentric to said axis and rotatably carried by the first mentioned member, the member and second member providing a chamber therebetween, fluid connections by way of said member and said second member to said chamber, and a device between said second member and the structure other than the one to which said member is secured for preventing rotative movement of the second member relatively to the last mentioned structure.

18. In a machine of the character described, a supporting structure, a structure revolvable about a vertical axis upon said supporting structure, and means for conveying a fluid between said supporting structure and said revolvable structure, said means including a swivel joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member to said chamber, and a device carried by and between said second member and the structure free of said swivel joint for preventing rotative movement of the second member relatively to the last mentioned structure, said device and said second member being adapted to have substantially a vertical movement relatively to each other.

19. In a machine of the character described, a supporting structure, a structure revolvable about a vertical axis upon said supporting structure, and means for conveying a fluid between said supporting structure and said revolvable structure,

said means including a swivel joint free of direct connection with one of said structures and consisting of a member concentric to the axis for the rotatable structure and secured to one of said structures, a second member concentric to said axis and rotatably carried by the first mentioned member, said member and second member providing a chamber therebetween, fluid connections by way of said member and said second member 10 to said chamber, and a tongue and slot interengaging device carried by and between said second member and the structure free of said swivel joint for preventing rotative movement of the second member relatively to the last mentioned structure, said device and said second member being adapted to have substantially a vertical movement relatively to each other.

20. In a machine of the character described, a supporting structure, a platform revolvable about a vertical axis on said supporting structure, and means for conveying a fluid between said supporting structure and said revolvable platform, said means including a swivel joint consisting of a member concentric to the axis for the platform 25 and secured to said platform, a second member concentric to said axis and rotatably carried by the first mentioned member to provide a chamber between said member and said second member, mechanism for fixing said second member against 30 rotation relatively to said supporting structure, and fluid connections by way of said member and said second member to said chamber.

21. In a machine of the character described, a supporting member, a member revolvable about a vertical axis upon said supporting member, and means for conveying a fluid between said supporting member and said revolvable member, said means including a swivel joint consisting of an element concentric to the axis for and secured to 40 the revolvable member, a second element concentric to said axis and rotatably carried by the first mentioned element to provide a chamber between said element and said second element, mechanism for fixing said element and said second element against rotation relatively to said revolvable member and said supporting member, respectively, and fluid connections by way of said element and said second element to said chamber.

22. In a machine of the character described, a supporting structure, a structure revolvable upon said supporting structure, and means for conveying a fluid between said supporting structure and said revolvable structure, said means including a swivel joint mounted upon one of said structures and free of direct connection with the other structure, and said swivel joint consisting of a member secured to one of said structures, a second member rotatably supported by means of a fluid-tight joint upon the first mentioned member, the member and second member providing a chamber therebetween, fluid connections by way of said member and said second member to said chamber, and a device between and secured to said second member and the structure other than the one to which said member is secured for locating said second member against rotative movement relative to the last mentioned structure.

tative movement relative to the last mentioned structure.

23. In a machine of the character described, a supporting structure, a structure revolvable about a vertical axis upon said supporting structure, and means for conveying a fluid between said supporting structure and said revolvable structure, said means including a swivel joint mounted upon one of said structures and free of direct connection with the other structure, and said swivel joint consisting of a member concentric to the axis for the rotatable structure and secured to one of said structures, a second member concentric to said axis and rotatably supported by the first mentioned member, the member and second member providing a chamber therebetween, fluid connections by way of said member and said second member to said chamber, and a device upon the structure other than the one to which said member is secured and engaging the second member for locating said second member against rotative movement relative to the last mentioned structure.

24. In a machine of the character described, a supporting structure, a structure revolvable upon said supporting structure, and means for conveying a fluid between said supporting structure and said revolvable structure, said means including a swivel joint mounted upon one of said structures and free of direct connection with the other structure, and said swivel joint consisting of a member secured to one of said structures, a second member rotatably supported by means of a fluid-tight joint upon the first mentioned member, the member and second member providing a chamber therebetween, fluid connections by way of said member and said second member to said chamber, and a tongue and slot interengaging device between and connected to said second member and the structure other than the one to which said member is secured for locating said second member against rotative movement relative to the last mentioned structure.

25. In a machine of the character described, a supporting structure, a structure revolvable about a vertical axis upon said supporting structure, and means for conveying a fluid between said supporting structure and said revolvable structure, said means including a swivel joint mounted upon one of said structures and free of direct connection with the other structure, and said swivel joint consisting of a member concentric to the axis for the rotatable structure and secured to one of said structures, a second member concentric to said axis and rotatably supported by the first mentioned member, the member and second member providing a chamber therebetween, fluid connections by way of said member and said second member to said chamber, and a tongue and slot interengaging device upon the structure other than the one to which said member is secured and engaging the second member for locating the second member against rotative movement relative to the last mentioned structure.
